UNITED STATES PATENT OFFICE.

WALTER H. DEUBLE, OF CANTON, OHIO.

DESIGN FOR A SPOON.

SPECIFICATION forming part of Design No. 25,204, dated March 3, 1896.

Application filed January 21, 1896. Serial No. 576,356. Term of patent 3½ years.

To all whom it may concern:

Be it known that I, WALTER H. DEUBLE, a citizen of the United States, and a resident of Canton, county of Stark, State of Ohio, have 5 invented and produced a new and useful Design for Spoons, of which the following is a full, clear, and exact description, reference being had to the accompanying drawing, making part of this specification.

10 My invention relates to a new and useful design for spoons; and it consists of a spoon having the configuration and ornamentation shown in the accompanying drawing.

15 The leading features of my design are a portrait-bust A of William McKinley on the upper end of the handle, a panel or name-space B on the lower portion of the handle C and the upper portion of the bowl is ornamented by a leaf-like scroll D, the leaf-like scroll E on the edge of the upper end of the 20 handle inclosing the portrait-bust, the lines F on the sides of the handle connecting the last-mentioned scroll with the bowl.

What I claim is—

The design for a spoon or similar articles, 25 as herein shown and described.

In testimony whereof I have hereunto set my hand this 8th day of January, A. D. 1896.

WALTER H. DEUBLE.
